UNITED STATES PATENT OFFICE.

JOHN P. CROWLEY, OF NEWPORT, KENTUCKY; ASSIGNOR TO THE CRAWLEY BOOK MACHINERY COMPANY, A CORPORATION OF KENTUCKY.

BEVEL-BOARD-CUTTING MACHINE.

No. 848,812.

Specification of Letters Patent.

Patented April 2, 1907.

Application filed April 27, 1905. Serial No. 257,640.

To all whom it may concern:

Be it known that I, JOHN P. CROWLEY, a citizen of the United States, residing at Newport, in the county of Campbell and State of Kentucky, have invented new and useful Improvements in Bevel-Board-Cutting Machines, of which the following is a specification.

My invention relates to improvements in bevel-board-cutting machines for beveling the edges of photo-mounts, tar and straw boards for book-covers, and the like, and is in the nature of an improvement on such machines as that invented by Messrs. Christie and Keck, as set forth in Letters Patent No. 422,726, issued March 4, 1890, or other machines for the same purpose employing a circular rotating knife to do the cutting.

My improvement is a grinding attachment normally out of contact with the knife, but adapted to be brought into grinding contact with the beveled edge thereof at will without removing the knife or unbelting the machine.

It is apparent that much time will be saved and the annoyance and danger of injury to operator and knife incident to handling such a part in cramped quarters avoided; but there is the added advantage of keeping the knife a true circle, no matter how much worn, for the shaft on which knife rotates and that on which grinder rotates are fixed in the housing. Consequently they are always the same distance apart.

My invention is illustrated in the accompanying drawings, in which—

Figure 1 is a side elevation of a rotary bevel-board cutter equipped with my grinding attachment with parts broken away to show operative mechanism. Fig. 2 is a section through the grinder-shaft and shifter mechanism. Fig. 3 is a section through the grinder.

A represents the machine - housing, to which is cast or attached prolongation of base A' and grinder-mechanism housing A².

To the main shaft B, driven by tight pulley C and provided with loose pulley C', is rotatively attached the feed-roll D, (if one is used,) also the gear b, which meshes with the gear e, rotatively attached to the knife-shaft E, to one end of which shaft knife F is relatively attached, so that knife and shaft are concentric.

At a convenient point on shaft B is rotatively attached the gear b', which is adapted to mesh with the gear g, which is rotatively attached to the grinder-shaft G. At a point on the shaft G adjacent to the knife F is rotatively attached a circular grinder H, of emery or like abrasive substance. Grinder H and shaft G are concentric. Grinder H is preferably cup-shaped and beveled outwardly on its outward side, so as to operatively contact with the beveled edge of the knife. Upon the shaft G and rotatively attached thereto by set-screw i' or in any other convenient way between bearings a and a' is placed a sleeve I, with annular groove i, adapted to receive stud-roll j. This stud-roll rotates upon stud j², which is securely attached to the hand-lever J. Hand-lever J is pivoted to the housing A² or a boss a² thereon by pin j¹.

Upon the shaft G between the bearing a and the sleeve I is placed a coiled spring K. When grinder is in position for use, as indicated by H, spring K is compressed. Then gear g is in mesh with gear b', transmitting rotary motion to the grinder. When grinder is in the position it would normally be held by action of spring K, (said position indicated by H'), the grinder is out of contact with the knife and not rotating, for gear g is not in mesh with gear b' but is in the position indicated by g'. If preferred, gear g may be elongated, so as to always be in mesh with gear b', and in which case either of gears g or b' may be normally loose upon its shaft and provided with a clutch to bring it into rotative relation with its shaft.

The operation of my invention is as follows: When the feed-roll or knife are still or rotating slowly and it is desired to sharpen the knife, press the lever J, then in position indicated by J', toward the grinder, compressing spring K, bringing gear g from position g' into mesh with gear b' and grinder H from position H' into contact with the knife F. Stud j² and roll j will have been advanced from their positions j³ and j', respectively, shown in dotted lines to those shown in full lines.

I claim as my invention and desire to secure by Letters Patent of the United States—

1. In combination with a machine having a revolving disk cutter for cutting beveled edges on boards, a rotary grinder whose

plane is parallel with the plane of the cutter, means for holding said grinder out of contact with the cutter, means for bringing said grinder into contact with the cutter, and 5 while in such contacting position independent means for rotating said cutter.

2. A grinder for revolving cutters composed substantially of the beveled rotary grinder, H, the spring, K, the sleeve, I, and 10 the gear, g, all mounted on the shaft, G, the lever, J, with its stud, j^2 , and roll, j , adapted

to engage the sleeve, I, and suitable mechanism for driving the gear, g, substantially as set forth.

In testimony whereof I have hereunto set 15 my hand in presence of two subscribing witnesses.

JOHN P. CROWLEY.
